WRAPPER PASTER ROLL

Sigurd Clausen, Brooklyn, N. Y., assignor to International Cigar Machinery Company, a corporation of New Jersey

Application September 16, 1939, Serial No. 295,173

14 Claims. (Cl. 131—21)

This invention relates to the fabrication of cigars, especially to the application of wrappers to the cigars, and more particularly to a wrapper paster mechanism for use in conjunction with a cigar machine of the type embodying a suctional transfer head provided with means to maintain the suctional effect and with mechanism to move the transfer head in a cycle during which the wrapper is carried from a cutting and shaping die to a rolling mechanism. Various machines of this type are known to those who are skilled in the art, and the present invention is applicable to the several machines.

The operation of applying the flag end of a wrapper to the pointed end of a cigar involves the provision of mechanism for supplying paste to the inner side of the flag end of the wrapper, and it is desirable that such mechanism shall not apply paste indiscriminately to the entire inner surface of the flag end, with the result that an excessive amount of paste exists upon the flag during the pasting operation and subsequent steps incidental to finishing the complete cigar.

Another disadvantage in operation of some makes of conventional wrapper pasters is that in some instances when the suctional transfer head has failed to pick up a wrapper, or the wrapper has been incorrectly spread over the perforated under surface of the transfer head, or is of insufficient size to cover the perforations in the head, the paster mechanism has acted to daub paste against the exposed perforated surface of the head, rendering the same undesirably adhesive and clogging the perforations so that the suctional effect is impaired, wrappers are misplaced and spoiled and considerable waste of material and loss of time ensues.

Under such conditions it is an object of the present invention to provide means for applying paste by a roller exclusively to the portion or portions of the flag end of a wrapper where it is necessary to accomplish proper adhesion to the pointed end of the cigar, without leaving any excess of paste, and preferably to apply the requisite paste in a substantially curvilinear trace conforming to the curved margin of the flag end of the wrapper, and leaving paste-free the area of the flag end within such marginal trace of paste, and which is to enwrap the point of the cigar.

A further object of the invention is to avoid the application of undesired paste to the exposed perforated surface of the transfer head in the absence of a wrapper thereon or if a wrapper be improperly shaped or positioned, and thus to

prevent soiling of the perforated surface of the head and clogging of its perforations.

Bearing in mind the above objects, the invention consists in the provision of a wrapper paster mechanism with a roller paster device for use in conjunction with a cigar machine of the type provided with a suctional transfer head having means to maintain its suctional effect and means to move said head through a predetermined transfer cycle preferably operating with a dwell at a given point, the wrapper paster mechanism comprising a paster roller and means to engage said paster device operatively with a cigar wrapper carried by said head, at said dwell; the invention consisting also in applying to the flag end of the wrapper a paste carrying salient constructed and arranged to be engaged with the flag end in a substantially curvilinear-trace conforming to the marginal contour of the flag end and leaving paste free the central area of the flag end bounded by said trace.

As ancillary features, the invention consists in associating the paste-applying roller with a paste reservoir which is moved bodily to cause traverse of the roller in its paste-applying position; and the invention consists also in means to incapacitate the elevating mechanism in the absence of a leaf upon the suction transfer head.

Other objects and features of the invention will appear as the description of the particular physical embodiment selected to illustrate the invention proceeds.

In the accompanying drawings, like characters of reference have been applied to corresponding parts throughout the several views which make up the invention, in which:

Fig. 1 is a view in elevation, partly in section, of a wrapper pasting mechanism in the construction of which the present invention has been embodied, and shown in conjunction with associated parts of a cigar machine;

Fig. 2 is an end elevation of the same;

Fig. 3 is a fragmentary detail view in end elevation taken on the line 3—3 of Fig. 1;

Fig. 4 is a development of the periphery of the paster roll, showing the paste-applying salient; and

Fig. 5 is a fragmentary detail view in plan showing the flag end of a cigar wrapper, with a curvilinear trace of paste applied to the under side thereof, as indicated in dotted lines.

Fig. 6 is a view in plan showing the transfer head and the mechanism for moving the head, shown in conjunction with the wrapper cutting die and the wrapping device.

In a now-preferred embodiment of the invention selected for illustration and description, the part designated by the reference character 10 is the base or a part of the supporting structure of a cigar machine of the type which is provided with a suctional transfer head 23 provided with means, indicated generally at 22, of conventional, or otherwise suitable form, for maintaining the suctional effect, and means (not shown) to move the transfer head in a predetermined transfer cycle for transferring a cut and shaped wrapper W from a cutting and shaping station to a rolling station, (not shown), the moving mechanism being suitably controlled to cause the head 23 to dwell at a pasting station defined by the position of the paster mechanism, as indicated in Fig. 1.

The supporting base 10 carries brackets 13 and 14, and a housing 12 with an enclosure 15 which supports a shaft 16 carrying a walking-beam lever 17, one arm of which is connected pivotally to a piston rod 18 and piston 19 working in a cylinder 20 which is in communication through a pipe 21 with the suction system of the cigar machine, and is in communication through a pipe 22 with the suction chamber of the transfer head 23, these parts being shown in somewhat fragmentary form, as they are well-known to those skilled in the art of fabricating cigar machines.

The other arm of lever 17 is provided with a nose 24 adapted to engage a step 25 of a cam lever 26 and in this latched position it retains the paster roll 27 in the position shown in Fig. 1. The lower end of lever 26 is equipped with a cam follower 28 held in engagement with a cam 29 by a tension spring 30. The cam 29 is fixed on a countershaft 31 supported by the brackets 13 and 14, said countershaft also carrying a bevel gear 32 meshing with a bevel gear 33 fixed on a driving shaft 34 carried by the stand 11. The shaft 34 is driven by suitable means from the main drive shaft of the machine (not shown).

The extending arm 35 of lever 26 supports one end of an adjustable rod 36 connected to an arm 37 of a bell crank lever 38 attached to a pivot shaft 39 mounted in hubs of a paste receptacle 40. The opposite end of shaft 39 supports an arm 41 which at its upper end, carries one end of a shaft 42. The shaft 42 at its other end is carried by the upper portion of lever 38. When the members 24-25 become unlatched by means to be hereinafter described, the cam 29, through link 36, allows arm 37 to ascend under the influence of spring 30 and turn shaft 39 thereby causing lever 38 and arm 41 to swing and raise the roll 27 to a position allowing the hump 43 of the roll to contact the wrapper and apply paste at the flag end of the same.

A cam 44 fixed on countershaft 31 actuates a cam follower 45 provided on a lever 46 pivotally mounted on another countershaft 47 carried by the brackets 13 and 14. The upper end of lever 46 supports one end of an adjustable rod 48 connecting to a lug 49 of a cross bar 50, said bar being attached to one end of shafts 51 and 52 slidably mounted in hubs of the stand 11. The adjustment of rods 48 and 36 may be accomplished by turning them in a conventional manner in their end shackles, the latter having right-and-left threads as usual in providing for such adjustments. The paste-reservoir carriage 40 is attached to shafts 51 and 52 by means of lugs 53, a depending arm 54 of the reservoir-carriage supporting a shaft 55 having a gear 56 fixed

thereto and adapted to mesh with a stationary rack 57 carried by brackets 66 attached to the stand 11. The other end of shaft 55 is equipped with a gear 58 mounted loosely on a bushing 69 fixed in bearing 54, the gear 58 meshing with a gear 59 fixed on a sleeve 68 turning on shaft 39, the gear 59 meshing with a gear 60 loose on shaft 42. The paster roll 27 is adjustably mounted on the hub of gear 60 by a set screw 67, providing means for setting the portion 43 correctly in respect to the flag end of the wrapper. Shaft 55 also carries a loosely mounted ratchet wheel 61 which is attached to gear 58, said ratchet wheel being provided with a tooth 62 adapted to be engaged and driven by a pawl 63 attached to an arm 64 fixed on shaft 55.

It is clear that as the shafts 51 and 52 are moved to and fro by cam 44, the gear 56, in engagement with the rack 57, when turning in one direction will cause the pawl 63 to engage and turn ratchet 61 one revolution and thereby turn gear 58 and gears 59 and 60. With the roll 27 in its raised position the turning of the same imparts rolling contact of the paste carrying salient 43 with the wrapper W, thus applying paste P to the same, as indicated in Fig. 5. When the gear 56 turns in the opposite direction, the pawl 63 becomes disengaged from its tooth 62 whereby the ratchet 61 and its gear 58 will remain stationary and consequently gears 59 and 60 will remain inactive during this cycle of the machine.

It is to be understood that in the wrapping operation the wrapper leaf W is suspended by suction from the carrier 23 which halts for a short time on its way to the wrapping device as already noted, to receive the paste; hence the latter is applied at this dwell position.

The salient or raised portion 43 of the paster roll 27 receives adhesive from a roller 65 fixed on sleeve 68 and which is partly submerged in the adhesive stored in reservoir 40.

When in the normal operation of the cigar machine, a wrapper covers the suction holes provided in the bottom of the carrier 23, the suction in chamber 20 is strong enough to pull down the piston 19 and thus unlatch members 24 and 25, permitting the cam 29 to allow the paster roll 27 to rise to a position in which its raised portion 43 will engage the wrapper. On the other hand, when the suction holes of the carrier 23 are open, as when running idle, or through the failure of the head to pick up a proper wrapper, or to pick up a wrapper properly, most of the suction in pipe 21 is spent through pipe 22, leaving in chamber 20 an insufficient amount to depress piston 19 and thus the members 24-25 will remain latched and the roll 27 will not be lifted, thereby preventing paste from being smeared onto the carrier 23, and so avoiding also the clogging of the perforations with paste.

Referring to Fig. 4, the raised portion 43 of the paster roll 27 is shaped to conform to the flag end of the wrapper W shown in Fig. 5. The outline of portion 43 is preferably slightly smaller so as to apply the paste P close to the edge of the wrapper and yet avoid smearing the carrier. The central area bounded by the substantially curvilinear trace P is thus left paste-free.

It is to be noted that the shaft 55 is free to turn in bushing 69 in order to prevent transmission of an undesired turning effect therefrom which might cause improper lifting of the roll 60.

There will now be described suitable mecha-

nism for moving the transfer head from the cutting die to the rolling mechanism by referring to Fig. 6, wherein is shown mechanism similar to that disclosed in my prior Patent No. 2,215,461, issued September 24, 1940.

Columns 107 and 108 of the cigar machine, the latter having a base 109, respectively support vertical shafts 110 and 120. On shaft 110 are mounted a horizontal cam 114 having a track (not shown), in its upper face, and a horizontal cam 116 having a track 117 in its upper face, and tracks (not shown) in its lower face.

Vertical shaft 120 has attached thereto a horizontal arm 121 provided with a roller 122 engaging the track in the upper face of cam 114. The free end of arm 121 carries a vertical stud 123 which, by means of suitable bearings supports the forked ends of a horizontal arm 127 for pivotal movement thereon. The wrapper carrier head 23 is rotatably mounted on the free outward end of arm 127. The upper fork end 126 of arm 127 is extended inwardly and carries two rollers 129 and 130 engaging the tracks in the lower face of cam 116. A boss 131 on arm 127 supports a stud 132 on which is pivoted a horizontal arm 133 having a roller 134 in engagement with track 117 of cam 116.

Carrier 23 is attached to the lower end of a flanged sleeve 135 turnably held in the free end of arm 127 by a cap 136, while to the upper flange end of sleeve 135 is affixed a gear 137 meshing with a gear sector 138 carried by the free end of arm 133. The gear 137 is preferably made in two coaxial relatively turnable adjustable narrow parts in order to take up the slack of the meshing teeth. Into sleeve 135 is loosely inserted a flanged sleeve 139 provided with a flange held therein by a disk 140 attached to gear 137 and overlapping the flange portion of the sleeve which forms the delivery end of a flexible tube 141 carrying the suction to the suction holes of the carrier head 23. Sleeve 139 passes through an aperture 143 provided in arm 133, this aperture being of the proper lateral extent to permit the required annular movement of arm 133. The other end of tube 141 is attached to the pipe 22 shown in Figs. 3 and 5.

The bunch B is delivered to the wrapping device 160. While the bunch B is being wrapped in the wrapping device 160, the wrapper W for the next following bunch is being cut on the die 171 by cutting rollers (not shown). The wrapper carrier head 23 picks up the wrapper W and carries it along the closed and irregularly curved path 159. As the carrier moves the wrapper to the wrapping position it is held stationary for a short period of time at the paster position thereof, designated 233 on the drawings. Following the application of paste the carrier moves on through its predetermined path in the wrapping position and the wrapper is completely applied to a bunch.

What is claimed is:

1. A wrapper paster mechanism for use in conjunction with a cigar machine of the type provided with a suctional transfer head having means to maintain its suctional effect, and means to move said head through a predetermined transfer cycle, operating with a dwell at a given station, said mechanism comprising a paster roll having a raised paste-applying surface of substantially curvilinear contour, and means to cause said raised paste-applying surface to be

engaged rotatively with said wrapper at said dwell.

2. A wrapper paster mechanism of the class described, for applying paste to the flag end of a cigar wrapper, preparatory to rolling, comprising a paste roller having a salient portion constructed and arranged to be applied rotatively to the flag end of a shaped cigar wrapper at a stationary position of the wrapper in course of transfer from a cutting and shaping station to a bunch-wrapping station, and means for rotating said roller while moving it rectilinearly along the stationary wrapper to apply paste to a predetermined area of the flag end of the wrapper.

15 3. A wrapper pasting mechanism having the features claimed in claim 2, wherein said salient portion has a substantially curvilinear contour conforming to the marginal contour of said flag-end, and adapted to leave paste-free a central 20 area of said flag end corresponding to the wrapper portion enwrapping the pointed end of a cigar.

4. A wrapper paster mechanism for use in conjunction with a cigar machine of the type provided with a suctional transfer head having means to maintain its suctional effect and means to move said head through a predetermined transfer cycle, operating with a dwell at a given station on said cycle: said wrapper paster mechanism comprising a supporting structure defining said station, a driving shaft co-ordinate in operation with the cigar machine, a counter-shaft, a paste reservoir carriage mounted to slide bodily upon guides on said supporting structure, and provided with a set of gears including a first gear, a second gear and a third gear, intermeshing in the order named, a bearing carried by said reservoir-carriage, a bushing held in said bearing, upon which bushing said third gear is mounted loosely, a fourth gear mounted loosely on said bushing, a stationary rack on said structure and with which said fourth gear meshes, acting, when the reservoir-carriage moves slidably, to rotate, and in turn to actuate relatively 45 the countershaft, third gear, second gear and first gear, a paster-roller co-rotative with said first gear, a bell-crank lever having arms and a shaft movable swingingly around the second gear axis, a feed roller rotatable with said second gear and having a portion of the periphery running within the paste supply and serving to feed paste to said paster roller, a cam-shaft operated by said drive shaft and having a first cam with connections to impart an oscillating motion to 50 said reservoir carriage, by virtue of which said fourth gear is rotated as it runs along said rack, serving to rotate in turn the set of gears, and also to operate the feed roller and paster roller, and a second cam on said cam shaft with connections 55 acting to impart planetary motion to said first gear, thereby to move it to a pasting station adjacent to the path of the transfer head when the reservoir carriage is moved in one direction, 60 and acting to retract said first gear and paster roller to an inoperative position at said station when the reservoir-carriage is moved in reverse.

5. A wrapper paster mechanism for use in conjunction with a cigar machine of the type provided with a suctional transfer head having means to maintain its suctional effect and means to move said head through a predetermined transfer cycle; said wrapper paster mechanism including a paste reservoir carriage and a paster roller with operating gearing and a cam-shaft

provided with cams, followers and connections constructed and arranged to operate said paster roller for the intended purpose, a second cam-shaft and a stepped cam on said last-named cam-shaft, a walking beam lever having on one arm a detent adapted to be engaged with said step to incapacitate said paster, and suction-operated means connected with the other arm of said walking beam, said last-named means including a cylinder, a piston working therein, responsive to a fluid-pressure differential as between cylinder spaces at opposite faces of said piston, one of said spaces being connected by a duct to said suctional transfer head, and said piston being so controlled that with normal suctional effect prevailing in the low pressure side of said cylinder it will trip the detent, as when the suction head is substantially sealed by a wrapper in transit, whereas when the absence of a wrapper opens the suctional head to atmosphere and diminishes the suctional effect, the piston is released from suction of an order adequate to trip the detent, and means to bias said detent to its position of engagement with said step to incapacitate said paster roller and hold it out of pasting position, thereby preventing said suction head from being soiled by paste in the absence of a wrapper to be pasted.

6. In a cigar machine having a carrier for an outspread flagged wrapper, adhesive applying mechanism for pasting the flag end of the outspread flagged wrapper on said carrier comprising in combination, a rotatable pasting element having a cylindrical pasting surface of such configuration as to engage the marginal portions of the flag while leaving interior portions of the flag unpasted, paste supplying means coacting with said element to apply paste to said surface, and means cooperating with said element and carrier to roll said surface across the flag on said carrier and apply the paste to said marginal portions of the flag.

7. In a cigar machine having a carrier for an outspread flagged wrapper, adhesive applying mechanism for pasting the flag end of the outspread flagged wrapper on said carrier comprising in combination, a rotatable pasting element having a cylindrical pasting surface of such configuration as to engage the marginal portions of the flag while leaving interior portions of the flag unpasted, paste supplying means coacting with said element to apply paste to said surface, and means cooperating with said element and carrier to roll said surface across the flag on said carrier and apply the paste to said marginal portions of the flag, said last-named means including mechanism imparting bodily movement of the axis of rotation of said element toward and away from said carrier to bring said surface in to and out of operating position relative to said flag.

8. In a cigar machine having a carrier for an outspread flagged wrapper, adhesive applying mechanism for pasting the flag end of the outspread flagged wrapper on said carrier comprising in combination, a rotatable pasting element having a cylindrical pasting surface of such configuration as to engage the marginal portions of the flag while leaving interior portions of the flag unpasted, paste supplying means coacting with said element to apply paste to said surface, and means cooperating with said element and carrier to roll said surface across the flag on said carrier and apply the paste to said marginal portions of the flag, said last-named means includ-

ing mechanism for imparting bodily movement to the axis of said element relative to said carrier in a direction generally parallel to the plane of the flag in order to roll said surface over the flag.

- 5 9. A device for pasting the flag of a cigar wrapper comprising a rotatable pasting element having a cylindrical pasting surface of such configuration as to engage the marginal portions of the flag while leaving the interior portions of the flag unpasted, a member supporting said element for rotative movement, and means permitting circumferential adjustment of said element on said member for setting said pasting surface correctly with respect to the flag end of the wrapper to be pasted.
- 10 10. Adhesive applying mechanism for a cigar machine of the type having a movable supporting device adapted to position a tobacco leaf section, said mechanism comprising an adhesive-reservoir, an adhesive-applying roller associated with said reservoir, means to move said reservoir bodily toward an adhesive-applying station adjacent to the path of said movable leaf supporting and positioning device, and means for elevating said roller from adhesive-receiving to an adhesive-applying position.

11. In a cigar machine having suctional means for supporting a tobacco leaf section in a stationary position for application of adhesive to the leaf section, a rotary member having a salient on its periphery adapted to apply adhesive within the margin of the stationary leaf section supported by the suctional means, and means for moving said member into engagement with the stationary leaf section and rotating said member while advancing it rectilinearly along the stationary leaf section to cause said salient to apply adhesive within the margin of the stationary leaf section.

40 12. In a cigar machine having suctional means for supporting a tobacco leaf section in stationary position for application of adhesive to one end of the leaf section, a rotary member having a salient on its periphery adapted to apply adhesive in a curvilinear trace within the margin of one end of the stationary leaf section supported by said means, and means for rotating said member while advancing it rectilinearly along the stationary leaf section to cause said salient to apply adhesive in a curvilinear trace within the margin of one end of the stationary leaf section.

13. Adhesive applying mechanism for a cigar machine of the type having a movable leaf supporting and positioning device adapted to position a tobacco leaf section, said mechanism comprising means for applying adhesive to a tobacco leaf section on said device, an adhesive reservoir, an adhesive applying roller associated with said reservoir, means to move said reservoir bodily toward a paste applying station adjacent to the path of said movable leaf supporting and positioning device, means for elevating said paster roller from a paste receiving to a paste applying position, devices for locking said paster roll elevating means against operative movement, and means to make said locking devices ineffective when a leaf section is properly supported by said movable supporting device.

70 14. In a cigar machine, the combination with a perforated support for an outspread tobacco leaf section, of mechanism for applying paste to the outspread tobacco leaf section on said support, said mechanism including a device for supplying adhesive, a paste applying roller arranged

to receive paste upon its periphery from said device, means to move said paste roller into position to apply paste to the outspread leaf section on said support, a suction chamber connected to said support for applying suction to the perforations of said support, and thereby suctionally retaining the outspread tobacco leaf section on

the support, and instrumentalities responsive to a change in suction created in said chamber by the absence of a leaf section on said support for preventing the operation of said means and thereby preventing the application of paste by said roller to the support.

SIGURD CLAUSEN.
